UNITED STATES PATENT OFFICE.

HENRY WALDO CUSHING, OF ROCKLAND, MASSACHUSETTS.

SHOE-FASTENER.

SPECIFICATION forming part of Letters Patent No. 746,927, dated December 15, 1903.

Application filed March 14, 1903. Serial No. 147,807. (No model.)

To all whom it may concern:

Be it known that I, HENRY WALDO CUSHING, a citizen of the United States, residing at Rockland, in the county of Plymouth and State of Massachusetts, have invented certain new and useful Improvements in Shoe-Fasteners; and I do hereby declare the following to be a full, clear, and exact description of the invention, such as will enable others skilled in the art to which it appertains to make and use the same.

My invention relates to improvements in shoe-fasteners; and it consists of an improved device for lacing shoes.

My invention will be understood by reference to the accompanying drawings, in which the same parts are indicated by the same letters throughout the several views.

Figure 1 represents a perspective view of a shoe supplied with my improved fasteners. Fig. 2 is a detail, on a larger scale, showing a portion of the top of the shoe with one of the fasteners secured thereto. Fig. 3 is a section along the line 3-3 of Fig. 2 and looking in the direction of the arrows, and Fig. 4 shows a modification in which the shank of the rivet is held between the folds of the leather.

A represents the top of the shoe, which is preferably constructed in the usual way.

B represents a loop, which is bent over to form an eye b, the parallel sides b' being fastened to the top of the shoe by a rivet C. This rivet preferably passes through the top of the shoe A, the lining A', and the members b' of the loop and has a cap c and a flange c', which flange is bent over, as shown in Fig. 3. The rivet is preferably hollow, as at c⁰, which hollow portion opens into the inside of the shoe to prevent the collection of dust therein, as would take place if it opened on the outside, and also the smooth cap c presents a neater appearance. The edge of the top A is scalloped, as at a, and the loops b are placed over these scalloped portions and are preferably curved inward, as at b². (See Fig. 2.) This shape furnishes a better lead for the shoe-string D and also makes the projecting edge

of the loop nearly flush with the edge of the top of the shoe, so that the two edges may be drawn close together, presenting a neat 50 appearance and also making the shoe substantially dust and water tight. Moreover, this construction causes the shoestrings to lie flush with the leather of the shoe and prevents the trousers or the skirt of the wearer 55 from abrading the same and also protects the strings from the blacking-brush. Moreover, the loops may be held between the top and the lining, as shown in Fig. 4, where the loop is secured to the lining A' and the end a' of 60 the top is passed over the loop, being cut away for the purpose, and then secured on the inside of the shoe. These loops may extend down to the bottom of the shoe-top or one or more pair of eyelets E may be supplied, as shown 65 in Fig. 1. Preferably the ordinary hooks (shown at B' in Fig. 1) should be used for the upper part of the shoe-top.

Practical use has demonstrated that a shoe-lacing rove in the manner herein described is 70 much more easily tautened and much more easily eased off or slackened up than the ordinary lacing rove through eyelets, as is now most commonly the case. Moreover, the shoe-string yields readily enough to automatically 75 adjust the tension uniformly on the instep, and thus comfortably fit the foot of the wearer. By having the loops let into the edge of the shoe-top, as shown, the edges of the top may be brought snugly together, and a neat appearance of the shoe is secured. Moreover, the curved shape of the loop enables the string to slide freely.

Having thus described my invention, what I claim, and desire to secure by Letters Patent of the United States, is—

1. The combination with a shoe having the edges of the top scalloped or indented, of a plurality of metal loops for the string secured over said indented portions and projecting 90 therefrom; substantially as described.

2. The combination with a shoe having the opposite edges of the top scalloped or indented, of a plurality of inwardly-curved metal

loops for the string secured over and projecting from said indented portions, substantially as described.

3. The combination with a shoe having the 5 opposite edges of its top indented or scalloped, of a plurality of curved metal loops mounted over said indented portions, with rivets securing said loops to the shoe-top and a string

passing through said loops, substantially as described.

In testimony whereof I affix my signature in presence of two witnesses.

HENRY WALDO CUSHING.
